DISCHARGE CONTROL ARRANGEMENT FOR
SNOW REMOVING MECHANISM

Walter E. Klauer, Dubuque, Iowa

Original application August 12, 1936, Serial No. 95,688, now Patent No. 2,144,311, dated January 17, 1939. Divided and this application August 12, 1936, Serial No. 95,693

3 Claims. (Cl. 37—43)

- The present invention relates to discharge control arrangements for snow removing mechanism and particularly to such mechanism adapted for use in removing snow from streets and highways.
- 5 It is concerned more particularly with such mechanism which is carried by a motor truck.
- This application is a division of my application Serial No. 95,688, filed August 12, 1936, now Patent No. 2,144,311.
- 10 In the past, the usual practice in the production of snow removing mechanism has been to mount the same permanently on a special truck. Such arrangement is comparatively expensive, and its expense is increased because it can be used
- 15 only during a short period of the year. The advantage of the use of trucks as compared to tractors is that such devices can move easily from one place to another as required at a high rate of speed, which is almost a necessity.
- 20 The primary object of the present invention is to provide power driven snow removal mechanism of a practical and efficient type which is arranged so that it can be readily mounted on and removed from a truck. Both the snow remover and the power unit for driving the same are easily and readily demountable. In this manner, the mechanism may be applied to a standard truck, which is used during the snow season to carry the snow removing mechanism, and may be
- 25 used during the remainder of the year for hauling purposes as a freight vehicle.

30 One difficulty particularly relating to snow removers of the rotary type which have a rotating or shiftable spout through which snow is ejected, movable so that snow will be thrown to one side or to the other of the snow remover, resides in the control of the position of such a spout. I have found that such control, which has hitherto been mechanical, is much simplified and easier if a hydraulic arrangement controlled from the cab of the truck is used for accomplishing this purpose.

35 Further objects and advantages of the invention will appear more fully from the following description, particularly when taken in conjunction with the accompanying drawings which form a part thereof.

In the drawings:

Fig. 1 is a side elevation of a snow remover embodying my invention and shown as mounted on a truck.

40 Fig. 1a is a continuation of Fig. 1, showing the power unit on a truck.

45 Fig. 2 is a top plan view of the arrangement shown in Fig. 1.

Fig. 2a is a continuation of Fig. 2 showing in top plan view the arrangement of Fig. 1a, with the power unit removed.

Fig. 3 is a top plan view showing the snow remover frame.

Fig. 4 is a top plan view of the hydraulic spout control.

Fig. 5 is a cross section on the line 5—5 of Fig. 6.

Fig. 6 is an end view of the mechanism of Fig. 4.

As shown in Fig. 1, the snow remover is mounted on a truck A of any standard type. This truck has a chassis consisting of longitudinal members 2 and a front cross member 4. The chassis is mounted on wheels 8, supported by axles such as the front axle 10. The wheels, preferably the rear wheels, are driven by a motor mounted in the hood 12 and provided with a radiator 14. The truck also has a cab 16 of any suitable type.

5 The truck also has a cab 16 of any suitable type. Mounted on the rear end of the truck is the power unit B. This power unit consists of a motor or engine 18 controlled by a throttle 20 which may be operated by a lever 24 inside the cab 16 through a flexible or Bowden cable 22. The unit B also includes a gasoline tank 26 for supplying fuel to the engine and a suitable pump 25 for forcing a liquid such as oil under pressure into a supply tank 28. The motor drives a clutch which is mounted in a housing 30 and is controlled through a link and lever system 32 by a lever 34 in the cab of the truck. The clutch is adapted to couple and uncouple a driving shaft to and from the motor 18.

10 C indicates in general the snow remover. It consists in the preferred form of a casing having side walls 38, a bottom wall and a scraper blade 40 and a rear wall 42. An opening in the rear wall 42 communicates with the interior of a fan casing 46 in which is mounted a fan for ejecting snow through the spout 48. Within the casing formed by walls 38, 40 and 42 are mounted three augers or conveyors 50 on horizontal vertically spaced axes. These augers are all driven, by a suitable chain drive mechanism 47 from a sprocket mounted on a shaft 49, to feed snow towards the center of the casing so that it can pass through the opening into the fan casing 46.

15 The snow removing mechanism is driven through a shaft mechanism running underneath the truck. The details of this drive are shown in my application for Snow removing mechanism, Serial No. 95,688 of which this case is a division, and which is now Patent No. 2,144,311.

20 The snow remover is carried by a frame having a transverse front top member 92, a transverse rear top member 94, top side members 97, vertical

members 96, and horizontal bottom members 88 which support the ends of a scraper forming the bottom portion of the wall of the auger casing.

The supporting and guiding arrangement for the plow includes vertically arranged T-shaped rails 114 and guide blocks or slide members 118 provided with T-shaped slots which fit over the arms of the T rails. Thus the blocks 118 are guided thereby for vertical sliding movement. Pins 122 pass through the blocks 118 and through the arms or brackets 124 secured on the cross member 94 of the plow frame, one of these brackets being arranged on each side of each block 118. Thus the plow frame is guided at both sides for straight up and down movement.

For raising and lowering the plow a special hydraulic arrangement is provided. Hydraulic cylinders 136 are mounted one on each side of the snow remover, in which are slidably arranged pistons 138.

Secured to the vehicle at points to the rear of the front thereof are uprights 140, which are braced by links 142 connected at one end to the uprights and at the other end to vehicle. Pivoted to the upper ends of the uprights are beams or links 144, preferably I beams. These beams carry blocks 146 to which are pivoted the pistons 138 and links 148 which at their other ends are traversed by the pins 122 in the neighborhood of the outer brackets 124.

Of course one of these lifting devices is provided on each side of the plow. It will be noted that this provides a simple and convenient mechanism for raising and lowering the snow remover without blocking in any manner the front of the radiator of the truck. This is a special advantage since when such trucks are in operation there is danger that the engine will become overheated if the radiator is blocked.

The hydraulic cylinders 136 are supplied with fluid under pressure through flexible pipes 152, releasable connections 154 and pipes 156. Pipes 156 are connected to a valve chest in which is a valve controlled by linkage system 160 through a handle 162 located in the cab of the truck. The details of this valve form no part of the invention, and it is sufficient to state that when the valve is moved to one position the piston will be caused to rise, while in the other position it will drop.

Fluid under pressure is supplied to the valve chest from the tank 28.

The fan casing 46 is mounted to rotate for example in the manner shown in the Wandscheer Patent No. 1,886,069. It is important to be able to shift the position of the spout 48 from one side to the other of the snow remover so that the direction of the stream of snow may be changed. For this purpose, I provide a hydraulic device for controlling the position of the fan casing. A lever 196 in the cab of the truck through a lever and linkage system 198 controls a valve in a valve box 200, supplied with fluid under pressure from the reservoir 28. Pipes 202 extend from this reservoir to the front of the truck and are connected through couplings 204 to flexible hoses 206.

Mounted on the cross member 94 is a bracket 208 which carries a pin 210 supporting one end of a hydraulic cylinder 212. The member 94 also

supports a pair of spaced U-shaped rails 214 between which slides a cross head 216. A piston 218 is slidable in the cylinder 212 has an extension 218 which is connected by a pin 220 to the cross head 216. A pin 222 carried by the cross head 216 forms a pivot for one end of a link 224 which at its other end engages a pivot pin 226 fixed in the rear wall of the fan casing. Pipes 206 on opposite sides of the plow are connected respectively to pipes 228 and 230 opening into opposite ends of the cylinder 212. It is evident that by admitting fluid under pressure to one side or the other of the piston the cross head 216 will be caused to move and will shift the spout 48 from one side to the other.

While I have described herein some embodiments of my invention, I wish it to be understood that I do not intend to limit myself thereby except within the scope of the appended claims.

What I claim is:

1. In a snow remover having adjustable snow discharging means, means to shift the position of said discharging means, said means comprising a fluid pressure cylinder extending transversely of the snow remover, a pair of opposed U-shaped rails at one end of the cylinder, a piston mounted in said cylinder and having its end guided between said rails, a link connected to the piston at one end and at its other end to the discharging means, and means to supply fluid under pressure to said cylinder.

2. In a snow removing mechanism having a snow receiving casing, a fan casing to the rear of said snow receiving casing, and an opening between said casings, a fan mounted in said fan casing, said fan casing having a spout at its periphery, and means to shift the position of said spout with respect to the snow removing casing, said means comprising a fluid pressure cylinder extending transversely of the snow remover, a pair of opposed U-shaped rails at one end of the cylinder, a piston mounted in said cylinder and having its end guided between said rails, a link connected to the piston at one end and at its other end to the fan casing, and means adjacent the driver's seat of the vehicle for controlling the supply of fluid under pressure to said cylinder.

3. In a snow removing mechanism mounted on a vehicle having a driver's seat, said mechanism having a snow receiving casing, a fan casing to the rear of said snow receiving casing, an opening between said casings, and a fan mounted in said fan casing, said fan casing having a spout at its periphery, means to shift the position of said spout with respect to the snow receiving casing, said last means comprising a fluid pressure cylinder extending transversely of the snow remover, a pair of opposed U-shaped rails at one end of the cylinder, a piston mounted in said cylinder and having its end guided between said rails, a link connected to the piston at one end and at its other end to the fan casing, means to supply fluid under pressure to the cylinder, and means adjacent the driver's seat of the vehicle for controlling the supply of fluid under pressure to said cylinder.

WALTER E. KLAUER.
